AUTOMOBILE WHEEL COVER

John R. Samsen, Livonia, Mich., assignor to Chrysler Corporation, Highland Park, Mich., a corporation of Delaware

Application March 31, 1959, Serial No. 55,284

Term of patent 7 years

(Cl. D14—30)

Fig. 1 is a front elevational view of an automobile wheel cover, showing my new design; and

Figs. 2 and 3 are sectional views taken on the lines 2—2 and 3—3, respectively, of Fig. 1.

I claim:

The ornamental design for an automobile wheel cover, substantially as shown.
